COMBINED FLOWER HOLDER AND BASE FOR A TABLE LAMP

Edwin I. Cole, Eagle, Wis., assignor to The Stiffel Company, Chicago, Ill., a corporation of Illinois

Application August 19, 1958, Serial No. 52,291

Term of patent 7 years

(Cl. D48—20)

Figure 1 is an elevational view of a combined flower holder and base for a table lamp showing my new design; Figure 2 is a view taken on lines 2—2 of Fig. 1; and Figure 3 is a perspective view taken on lines 3—3 of Fig. 1.

I claim:

The ornamental design for a combined flower holder and base for a table lamp, as shown and described.
